UNITED STATES PATENT OFFICE.

ADELARD JOSEPH DUBEE, OF GLENS FALLS, NEW YORK.

SPARK-PLUG CLEANER.

Application filed December 31, 1921. Serial No. 526,447.

To all whom it may concern:

Be it known that I, ADELARD J. DUBEE, a citizen of the United States, residing at Glens Falls, in the county of Warren and 5 State of New York, have invented new and useful Improvements in Spark-Plug Cleaners, of which the following is a specification.

This invention relates to spark plug cleaners, and the principal object is to provide a 10 device of this nature which shall be simple of construction, cheap to manufacture, and highly efficient for the purpose for which it is designed.

Another object is to produce a device of 15 this nature whereby the interior of the spark plug may be reached.

With these and other objects in view, the invention resides in certain novel construction and combination and arrangement of 20 parts, the essential features of which are hereinafter fully described, are particularly pointed out in the appended claim, and are illustrated in the accompanying drawing, in which:—

25 Figure 1 is a view of a spark plug cleaner constructed according to my invention and formed both as to handle and blade in a single rigid piece.

Figure 2 is a view of a similar device constructed with a jointed blade foldable into the handle.

30 Figure 3 is a collective view showing several shapes of cross section which may be had by the blade according to the requirements of the particular plug to be cleaned.

35 Like characters of reference refer to like parts in all views.

Referring to the drawing in detail, 10 represents the handle which may be either 40 integral with the blade as shown in Figure 1 of the drawings or entirely separate therefrom as shown at 10' in Figure 2; and 11 represents the blade generally. It will be noticed that the blade 11 tapers from end 45 to end, and on both sides in the preferred form shown. The blade may have any de-

sired cross sectional shape. The long narrow taper of the blade makes it such that it can be inserted in the plug to any desired length and utilized for the purpose of scraping the carbon, soot or dirt therefrom. It also permits of the entire length of the blade being used in the cleaning operation.

It is particularly desired to point out that the difference between this device and a flat 50 blade is that it gives a greater length of cleaning edge and is more readily capable of probing the most remote portions of the plug.

Besides the taper feature, one side of the 60 blade as at 13 is smooth so as to form a scraper and the other edge is toothed so as to form elements for breaking up the substance which is desired to be removed. It will therefore be seen that I have produced 65 a device which while exceedingly simple, includes all necessary elements required for a perfect cleaning of a spark plug.

While I have described what I deem to be the most desirable embodiment of my invention, it is obvious that the details may be varied without in any way departing from the spirit of my invention, and I therefore do not limit myself to the exact details of construction herein set forth nor to anything 70 less than the whole of my invention limited only by the appended claim.

What is claimed as new is:—

A spark plug cleaner comprising a relatively thin elongated blade, a handle formed 80 therewith, the said blade tapering from its point of connection with said handle toward the free end thereof, teeth formed on one side of said blade whereby material accumulating in a spark plug may be broken 85 up, and a knife edge formed on the other side of said blade for scraping the substance from said spark plug after the same has been broken up by said toothed edge.

In testimony whereof I have affixed my 90 signature.

ADELARD JOSEPH DUBEE.
